Thomas F. Glenn,

UNITED STATES PATENT OFFICE.

THOMAS F. GLENN, OF ARDMORE, PENNSYLVANIA.

ARTIFICIAL TOOTH.

1,163,141.

Specification of Letters Patent.

Patented Dec. 7, 1915.

Application filed April 7, 1915. Serial No. 19,629.

To all whom it may concern:

Be it known that I, THOMAS F. GLENN, a citizen of the United States, and a resident of Ardmore, in the county of Montgomery, State of Pennsylvania, have invented certain new and useful Improvements in Artificial Teeth, of which the following is a specification, reference being had to the accompanying drawings.

10 My invention relates particularly to that class of artificial teeth which are commonly designated as interchangeable facings, and is directed especially to the means for detachably connecting the porcelain tooth body, comprising the facing, to a bridge-piece, plate, or other suitable mounting.

The principal objects of my invention are, to provide a tooth facing which is of simple construction, inexpensive to manufacture, 20 and which may be readily removed and replaced and firmly engaged with respect to its mounting by a rectilinear movement in the direction of the plane of the "bite", whereby the opposed relatively angular 25 surfaces of the facing and its mounting may accurately conform without interference.

Specifically stated, my invention comprehends a tooth facing arranged to be connected with a backing, and having its "bite" sloping labially toward its incisive edge, 30 which may be protected by said backing, and having an anchor recess for the engagement with a suitable projection on said backing disposed in a plane substantially parallel to 35 the plane of said "bite".

My invention also includes all of the various novel features of construction and arrangement hereinafter more definitely specified.

40 In the accompanying drawings, Figure 1 is a central longitudinal sectional view of a tooth facing and its backing embodying a convenient form of my invention, a portion of the backing being shown in elevation for convenience of illustration, and the facing being shown in dot and dash lines in an alternate position; Fig. 2 is a transverse horizontal sectional view of the tooth and backing shown in Fig. 1, taken on the line 2—2 45 in said figure; Fig. 3 is a central sectional view taken longitudinally through a tooth and backing, having the characteristics of the tooth shown in Fig. 1, but embodying a slight modification thereof, a portion of the 50 backing being shown in elevation for convenience of illustration, and the facing being

shown in dot and dash lines in a possible alternate position; and Fig. 4 is a transverse horizontal sectional view taken through the tooth shown in Fig. 3, on the line 4—4 in 55 said figure.

In the form of my invention shown in Figs. 1 and 2, the tooth body 5, which may be preferably composed of porcelain, has its lingual face formed of relatively angular 60 surfaces comprising the "ridge-lap" 6, "bite" 7, and intervening lingual surface termed the "shut" 9, said "ridge-lap" and "bite" being disposed in labially oblique relation with respect to the "shut" surface 9. The body of the tooth facing 5 is provided in its lingual face with a recess which may be in the form of an undercut slot or groove 10 extending longitudinally of the facing, which in the form of my invention 75 shown in Figs. 1 and 2 comprises a broad, flat cavity 12 having the edges 13 and 14 of the surfaces 15 and 16 of its lingual wall disposed in a plane which is substantially parallel to the plane of the "bite" surface 7. 80

The lingual face of the tooth above described is arranged to be clothed by the backing comprising the relatively angular walls 20, 21 and 22 respectively overlying the "ridge-lap", the "bite" and the "shut" 85 surface of the lingual face of the tooth facing body 5. Said backing is provided with an anchor bracket or tongue 23 which is arranged to snugly fit the cavity 12 in the tooth facing 5, being connected with the 90 backing wall 22 by the relatively narrow web 25, which is preferably arranged to accurately fit the slot or groove 10 in the tooth facing body 5.

The lingual surfaces of the tongue 23 are 95 disposed in substantially parallel relation to the "bite" wall 21 of the backing, so that the tooth facing 5 may be engaged with said backing by a rectilinear movement from the incisive edge of the backing, gingivally, 100 from the position shown in dot and dash lines to the position shown in full lines, wherein the opposing surfaces of the tooth and its backing absolutely conform to each other and snugly fit together. 105

It may in some cases be convenient to dispense with the backing wall 20, for instance, where the facing 5 is employed as an intermediate tooth in bridgework, such as shown in Figs. 3 and 4, in which instance the 110 "ridge-lap" may abut directly against the gums of the patient.

The form of my invention shown in Figs. 3 and 4 comprises the tooth facing 26 having the "ridge-lap" 27, "bite" 28, and intermediate "shut" surface 29, and comprises 5 a recess in the form of an undercut slot or groove 30 forming the cavity 31. The edges 32 and 33 of its lingual surfaces 34 and 35 are disposed in a plane substantially parallel to the "bite" surface 28, while the 10 labial wall 36 may be of any desired configuration and be preferably disposed to form a wedge-shaped cavity, as best shown in Fig. 3.

The tooth facing body 26 may be provided with a backing comprising the relatively angular walls 38 and 39 respectively arranged to extend over the "bite" 28 and "shut" surface 29 of said facing body. Said backing is provided with an anchor 20 bracket or tongue 40 conforming to the cavity 31 and connected with the wall 39 of the backing by a relatively narrow rib 41, which is preferably arranged to snugly fit the slot or groove 30. In this form of my invention, 25 as in the form shown in Figs. 1 and 2, the tooth facing 26 may be directed, as shown in dotted lines, from the incisive edge of the backing, gingivally, to the position shown in full lines in Fig. 3, with the 30 lingual surfaces 34 and 35 of the cavity 31 in contact with the corresponding lingual surfaces of the tongue 40, and the lingual surface of the "bite" 28 in contact with the labial surface of the wall 38 of said backing. 35

I am aware that various forms of tooth facings have been devised wherein attempts have been made to so form the backing and facing as to provide a rigid engagement of 40 said facing with said backing, and to provide for protecting the incisive edge of the facing with an inclined bite protecting plate, but so far as I am aware, no such tooth structure has been devised that may be engaged with the backing by a rectilinear movement in a plane parallel to the plane 45 of the "bite", and wherein the anchor member and bite protecting member coöperate to guide the facing into its final position.

50 It is to be understood that the gingival wall 20, shown in Fig. 1, may be omitted,

or that the backing shown in Fig. 3 may be provided with such a wall without in any way affecting the utility of the backing as contemplated.

I do not desire to limit my invention to the precise details of construction and arrangement herein set forth, as it is obvious that various modifications may be made therein without departing from the essential features of my invention as defined in the appended claims.

Having thus described my invention, I claim:

1. A tooth having its lingual face formed 65 of relatively angular surfaces comprising a "shut" and a relatively oblique "bite", and provided with an undercut recess in the "shut" surface, and having the edges of the lingual surfaces of said recess disposed 70 in a plane substantially parallel to the oblique "bite" surface of said tooth.

2. In a tooth, the combination with a facing having relatively angular "shut" and "bite" surfaces, and an undercut recess 75 in said "shut" surface having the edges of its lingual surfaces disposed in a plane substantially parallel to said "bite" surface, of a backing for said tooth having relatively angular walls conforming to the lingual face 80 of said tooth, and having a tongue substantially conforming to said recess and connected in oblique relation to one of said walls by a relatively narrow web, and extending substantially parallel to the other 85 wall.

3. A tooth backing having relatively angular walls respectively arranged to engage the "shut" and "bite" surfaces of a tooth facing, and having a tongue which is arranged to engage a suitable anchor recess in said tooth facing, and which is connected in oblique relation to one of said walls and disposed substantially parallel to the other 90 wall.

In witness whereof, I have hereunto set my hand this 6th day of April, A. D., 1915.

THOMAS F. GLENN.
